UNITED STATES PATENT OFFICE.

JEANNETTE C. SHINN, OF PADUCAH, KENTUCKY.

CARD GAME.

1,312,278.

Specification of Letters Patent.

Patented Aug. 5, 1919.

Application filed November 21, 1918. Serial No. 263,640.

To all whom it may concern:

Be it known that I, JEANNETTE C. SHINN, a citizen of the United States, residing in Paducah, McCracken county, Kentucky, have invented certain Improvements in Card Games, of which the following is a specification.

My invention relates to games played with cards; and the object of my invention 10 is to provide an interesting and instructive card game which embodies certain educational features and is particularly adapted to be played by young children.

In developing my improved game and for 15 use in playing the same, two sets of cards are provided; one set of so-called "object" cards, which need not exceed twenty-six in number, and a set of "letter" cards, which should be in sufficient quantity and diversity 20 to spell the words constituting the names of the objects portrayed on the "object" cards.

The playing of my improved game involves thought on the part of the players to properly designate the objects portrayed 25 on the "object" cards; a reference list forming a key being provided to settle any dispute respecting the object named, and the proper manner of spelling the same may also be checked by the reference list.

30 These and other features of my invention are more fully described hereinafter, reference being had to the accompanying drawings, in which:

Figure 1, is a face view of an "object" 35 card, and

Fig. 2, illustrates a plurality of "letter" cards.

The prime object of this game is educational. To this end a full pack of cards includes 40 two sets; "letter" cards and "object" cards. Each of the "object" cards will preferably have pictures of two objects portrayed thereon; such pictures may occupy one-half of the card, and each picture may

45 take up substantially one-fourth of the entire surface of a card. It will be obvious, however, that the "object" cards may have one picture or more than two; that the arrangement or size is immaterial, and that 50 such picture or pictures may occupy any position on the card. By preference the pictured objects so portrayed on any one card may be such as to have the same letter, so that a key letter indicating to a player the

initial letter of the name of the objects portrayed may be carried directly by the card. 55

These "object" cards may be as many or as few as desired; relatively speaking, twenty-six "object" cards may be employed, one for each letter of the alphabet. As each card 60 may bear two or more objects, a set of twenty-six cards may have the names of at least fifty-two objects to spell. Of the "letter" cards there will be provided as many as may be needed and in proper diversity to spell the words representing the names of the objects of the several "object" 65 cards. It may not be necessary to provide a large amount of the "letter" cards, since it is quite possible to use the same more than once, as will hereinafter appear.

The objects pictured on the "object" cards are preferably simple ones that may be covered by a name having a relatively small number of letters, and it is more or less desirable and will add zest to the game to have objects to which more than one name might be applied. Whether the names which may be applied could be used would be determined largely by the initial or key letter 75 carried by the "object" card. In addition to this key letter, the card may be provided with numbers indicating the objects—"1" and "2" for instance, and these numbers may be employed with the letters in connection 80 with the reference list and refer to the words noted on such list as representing the different objects carried by the cards with the corresponding letters and numbers, to wit: A_1^1 ; B_2^1 , and so on. 85

The "letter" cards are preferably plain, and they may have a white face with a single letter in the center of the same, or the same letter oppositely faced so as to have 95 single letter value, and the four corners of the several cards may have the usual pip markings.

In the "object" card portrayed in the drawing, I have shown the representation 100 of a "mask" and the representation of a "mill"; the card additionally bearing the "key" letter "M," the initial letter of the words indicating the objects on the card, and these objects will be noted on the reference 105 list as M_2^1 .

By preference the "object" cards have

backs of one color or design, and the "letter" cards have backs of another color or design, so that they can be readily sorted after any game has been completed preparatory to shuffling and dealing for the next game.

5 In playing the game, the method may be substantially as follows:

Any number of players up to eight may take part, and the cards may be dealt in the usual manner; first to the left of the dealer; each player, including the dealer, receiving three "object" cards and four "letter" cards, although the number of the "letter" cards dealt may be greater or less as may be desired, and this may also depend upon the number of players. The balance of the "letter" cards may be placed on the board or table and constitute a bank from which the players may draw under conditions which will appear hereinafter. The game may commence by the first player to the left of the dealer placing an "object" card on the board or table, then announcing the name of one of the objects portrayed thereon as the one he (or she) intends to spell and proceeding to spell the same. In doing this, the player is guided largely by the "letter" cards held, for in selecting the "object" card played the natural impulse would be to select one from those dealt which could be spelled wholly or in part by the use of the "letter" cards in the player's hand. The player has the privilege, therefore, after playing an "object" card, of laying down as many cards to spell the name of the object chosen as his (or her) hand will supply, and when his (or her) hand is exhausted of available cards, of drawing one card from the pile of "letter" cards which have not been dealt, (but only one card may be drawn). If the player succeeds in completing the word before the next player's turn arrives he (or she) takes a trick.

If the player who led the "object" card is unable to complete the spelling of the name of the object announced by the cards from his (or her) hand or by the use of that drawn from the pack, the right to complete the word passes successively to the players to the left, and the one completing the word takes the trick; the play continuing in the same manner and with the right to draw one card from the pack.

After any player of an "object" card has announced the name of the object he (or she) proposes to spell, such announcement is subject to challenge by any one of the players as to the correctness of the name of the object portrayed, and the manner of spelling the word is also subject to challenge as to correctness. These friendly disputes can only be settled by reference to the list containing the names of all the objects portrayed. If the player challenged is wrong, 65 the person who made the challenge takes the

trick without further playing of any of his cards. If the challenger is wrong, he may be penalized by losing one "object" card, or in any other suitable manner.

As the cards are provided with the representation of two objects, it may be in order for any subsequent player instead of proceeding to complete the first word commenced, to name the second object on the card, and to proceed to spell it in the manner described with reference to the first object, and the player completing the spelling of such word takes the trick. In lieu of this he may lay down an "object" card, announce the name of one of the objects, and proceed to spell it. Preferably, however, the following method of play may be pursued: After a word has gone the rounds two or three times, as may be prearranged, without being spelled, the player next in turn may have the right to start in circulation the other object on unsuccessful card, of finishing the object first named should the card drawn permit, or of laying down from his (or her) hand an "object" card and making a choice of objects to begin with. Then the player next to him, and so on will have a choice of four objects, as the unsuccessful card will be left on the table to be used in this way until one of the four objects is spelled. Play may continue until the "object" cards in the hands of the players are exhausted, and the person having the most tricks wins the game, or in lieu of this, the person who first takes a predetermined number of tricks may be counted the winner.

In order that the "letter" cards need not be multiplied to an unwieldy extent, it is entirely practicable to use them a second time after any word has been spelled, by placing them with the other cards lying in the center of the table or with the pile thereon. If a pile is employed, the used cards may preferably be returned to the bottom of the same.

It will be seen therefore that my game comprehends the use of "object" cards, each of which may carry one or a plurality of objects, with a key letter indicating the initial letter of the objects portrayed; the name of each object commencing with such key letter, and for the purpose of spelling the words indicating the objects, a set of "letter" cards is provided sufficient in number and diversity of letters to insure the proper spelling of the words indicating the various objects portrayed upon the several "object" cards.

While I have shown an "object" card with the objects portrayed side by side, it is within the scope of my invention to arrange the objects in any way upon the cards; in opposite corners for instance, to show a plurality of objects having different

initial letters instead of the same initial letter for both objects, and to provide "object" cards with any number of objects that can be conveniently grouped thereon; such 5 objects being accompanied by a common key letter or with a different key letter for each object portrayed. The "letter" cards may bear a pair of the same letters, disposed in opposite directions, so as to avoid turning them in the hand or when laying them on the board or table. In some instances it 10 may be desirable to provide "letter" cards having a pair of different letters, either one of which may be used in spelling a word.

15 I claim:

1. A deck of playing cards, comprising a plurality of sets of cards; each card of one set having an object portrayed thereon with a key letter indicating the first letter of

the name of such object, and a second set 20 comprising a plurality of "letter" cards whereby the name of such object may be spelled.

2. A deck of playing cards, comprising a plurality of sets of cards; each card of one 25 set having a plurality of objects portrayed thereon with a common key letter indicating the first letter of the names of such objects, and each card of a second set having a letter whereby the names of such objects 30 may be spelled.

3. A deck of playing cards, comprising two sets of cards; one set having objects pictorially displayed thereon, and the other set having letters whereby the names of such 35 objects may be spelled.

JEANNETTE C. SHINN.
